PROTECTIVE DEVICE FOR THE COIN ADMISSION OF COIN FREED MACHINES

Filed Dec. 14, 1929

UNITED STATES PATENT OFFICE

WILLIAM GEORGE COLEMAN, OF DUNEDIN, NEW ZEALAND

PROTECTIVE DEVICE FOR THE COIN ADMISSION OF COIN-FREED MACHINES

Application filed December 14, 1929, Serial No. 414,055, and in New Zealand April 18, 1929.

This invention relates to coin-freed machines.

Hitherto owners of such machines have been subjected to considerable trouble and annoyance as the result of people mischievously inserting in the coin slots articles such as pieces of broken glass, wire, or other things which jamb or injure the mechanism and thus render the machines inoperative.

10 It is the object of the present invention to provide a protective device of novel and special construction for mounting over the coin entrance of such machines, the said device being such that it will be incapable, or practically incapable of admitting anything but the required coin or a disc closely approximating to the same in diameter and thickness.

In order that the nature of the invention and its construction may be clearly understood, it will now be fully described and explained with reference to the accompanying drawings, in which:

Fig. 1 is a front view of the device,

Fig. 2 is a rear view of the same showing 25 the parts in their normal positions,

Fig. 3 is a similar view to that of Fig. 2 but showing the parts in the positions which they assume when a coin is in process of insertion, and,

30 Fig. 4 is a longitudinal section through the device along the line IV—IV, Fig. 1, the parts being here shown in full lines in their normal positions while the corresponding positions which such parts assume when a coin is being 35 inserted is indicated in dotted lines.

The construction includes a casing comprising a base-plate 1 having a coin-slot 2 enclosed by a forwardly protruding formation 3 containing a flanged entrance 4 of the correct shape and dimensions to closely admit the required coin as 5 to the said slot 2, the construction thus far described being generally similar to that of certain coin entrances at present in use.

45 According to the present invention however there is associated with the slot 2 a plate 6 slidable transversely thereacross and adapted in one position as here shown in Figs. 1, 2, and in full lines, Fig. 4, to cover the slot 2 and in another position to uncover such slot

as by presenting in register therewith a slot 7 formed in the plate 6, as clearly shown in Fig. 3, the said slidable mounting of the plate 6 being conveniently achieved as by the provision of guides 8 upon the rear side 55 of the plate 1 and between which guides the said plate 6 is received.

The said sliding movements of the plate 6 are attained by the provision of a pair of levers 9 and 10 each having one end fulcrumed as at points 11 and 12 respectively within the protruding formation 3 and from whence such levers extend rearwardly through slotted openings 13 and 14 through the base 1, one to either end of the slot 2. 60

The rear ends of the levers 9 and 10 extend respectively through oppositely arranged oblique slots 15 and 16 in the sliding plate 6 and beyond which the extremities of such levers are provided with inwardly returned 70 formations 18 and 19 extending in alignment with the slot 2 and adapted to bear against the rear face of the plate 6, thereby keeping the latter in contact with the base 1. 65

The said levers 9 and 10 are spring-controlled to cause their free or rear ends to move mutually inward and thus assume positions at those ends of the oblique slots 15 and 16 which are closest together, thereby sliding the plate 6 into the position in which it covers the slot 2, as shown in Figs. 1 and 2 and in full lines Fig. 3, such control being conveniently accomplished, as here shown by the provision of a tension-spring 20, Figs. 2 and 3, interconnecting the said levers at or near 75 their rear ends.

The said levers 9 and 10 are provided also with lugs or formations 21 and 22 respectively which when the parts occupy their normal positions, as above explained, protrude slightly within the coin-entrance 4, the arrangement being such that when a coin is inserted in such entrance the edges of such coin will come in contact with the said lugs thereby forcing the levers 9 and 10 apart 80 against the tendency of the spring 20. 90

When so forced apart the levers will move towards the other ends of the oblique slots 15 and 16, thereby sliding the plate 6 into the position in which it uncovers the slot 2 100.

thus permitting the coin to pass therethrough as shown in Fig. 3 and in dotted lines Fig. 4.

After passing through the slot 2 the edges of the coin will engage between the returned formations 18 and 19, which, on account of the tendency of the spring 20 upon their respective corresponding levers, will bear firmly upon the edges of such coin and so 10 serve to propel the latter into the machine when the points of bearing of such returned formations upon the edges of the coin passes beyond the diametrical line of the latter.

The operation of the device is briefly as 15 follows:—

The coin slot being normally closed by the plate 6, it will be impossible to insert anything therethrough into the machine without simultaneously forcing apart the levers 9 and 20 10, an operation that cannot conveniently be achieved except by the insertion within the coin-entrance of the required coin or a disc closely approximating thereto.

When the correct coin is inserted however 25 in the said coin-entrance it will practically occupy the whole of the interior thereof and in forcing apart the levers will bring the sliding plate into the required position to uncover the coin-slot thereby permitting such 30 coin to pass therethrough into the machine which being accomplished the levers will immediately return to their normal positions under action of the spring, thereby causing the plate 6 to again close the slot.

35 I claim:

1. A protective device for the coin entrances of coin-freeed machines comprising the combination with a base-plate adapted for mounting over said entrance, a coin-slot 40 in said base-plate and a forwardly protruding formation providing a coin entrance enclosing said slot, of a plate slidable transversely across said slot, to occupy one position in which it covers and another position in which it uncovers said slot, a pair of levers each fulcrumed within said protruding formation and extending rearwardly through slotted openings in said base-plate one to either end of said coin-slot, a pair of 45 oppositely arranged oblique slots in said sliding plate and through which the rear ends of said levers extend spring controlling means tending to move the rear ends of said levers mutually inward thereby to cause them to occupy positions in said oblique slots in which they place said sliding plates in the coin-slot-closing position, and formations upon said levers protruding within said coin entrance to be engaged by the edges of a coin 50 inserted therein thereby to cause said levers to be forced apart and assume positions in said oblique slots in which they place said sliding plate in its coin-slot-opening position.

60 2. A protective device for the coin admis-

sions of coin-freeed machines, as defined in claim 1, characterized in that the rear ends of said levers are provided with inwardly turned formations disposed in alignment with said coin-slot to keep said sliding plate 70 in contact with the base and to engage a coin inserted as aforesaid through said coin slot and propel such coin into the machine.

In witness whereof, I have hereunto set my hand.

WILLIAM GEORGE COLEMAN.
